His ATTORNEY.

UNITED STATES PATENT OFFICE.

ALFRED JOHN MEAKIN, OF TUNSTALL, ENGLAND.

DESIGN FOR A PLATE OR SIMILAR ARTICLE.

No. 38,861.

Specification for Design.

Patented Oct. 22, 1907.

Application filed September 12, 1907. Serial No. 392,599. Term of patent 7 years.

To all whom it may concern:

Be it known that I, ALFRED JOHN MEAKIN, a subject of the King of England, and a resident of Tunstall, in Staffordshire, England, have invented a new, original, and ornamental Design for a Plate or Similar Article, of which the following is a specification.

In the accompanying drawing, the figure is a plan showing the design on the plate.

What I claim is:
The ornamental design for a plate or similar article as shown.

ALFRED JOHN MEAKIN.

Witnesses:

WALTER BADDELEY,
EDWARD JOHN HUGHES.
